UNITED STATES PATENT OFFICE.

RAGNVALD M. NICOLAYSEN AND HARLEY H. LA VERCOMBE, OF DETROIT, MICHIGAN.

GRINDING-MACHINE.

1,101,505.

Specification of Letters Patent. Patented June 23, 1914.

Application filed October 18, 1912. Serial No. 726,529.

To all whom it may concern:

Be it known that we, RAGNVALD M. NICOLAYSEN, a subject of the King of Norway, and HARLEY H. LA VERCOMBE, a citizen of the United States of America, residing at Detroit, in the county of Wayne and State of Michigan, have invented certain new and useful Improvements in Grinding-Machines, of which the following is a specification, reference being had therein to the accompanying drawings.

The invention relates to grinding machines and has for its particular object the obtaining of a construction adapted for the renewing of milling cutters.

Where milling cutters are formed by machining the annealed metal and subsequently hardening, the cutters thus formed may be sharpened by grinding on an ordinary grinder wheel, but eventually the teeth will be completely ground away, which is the limit of life of the cutter. The blanks cannot be satisfactorily annealed and re-cut, as there is great danger of cracking, particularly when the metal is re-hardened. This is especially true of high-speed steel.

With our improved grinder the cutters may be refashioned without annealing and their life thereby greatly prolonged.

In the drawings: Figure 1 is a sectional plan view of the machine; Fig. 2 is a longitudinal section thereof; Fig. 3 is a cross section; Fig. 4 is a view similar to Fig. 1, with the section in the plane of the arbor; and Fig. 5 is a side elevation of the feed mechanism.

Generally described, our improved grinding machine comprises a rotatively adjustable work-holding spindle; indexing mechanism, controlling the adjustment thereof; a grinder wheel; means for intermittently reciprocating said grinder wheel toward and from the periphery of the work upon said holder, said means operating alternately with the operation of said indexing mechanism; and the machine is further provided with automatic feeding means by which, at the completion of each cycle of the work-holder, the limit of forward movement of the grinder is adjusted so that the successive grinding cuts will be deeper. This action continues until the required depth of cut is obtained, whereupon an automatic trip disengages the

feed mechanism and prevents further cutting.

In detail, A is a suitable frame, on which is mounted the work-holding spindle B, preferably arranged with its axis vertical.

C is a reciprocatory slide mounted upon guide-ways D upon the frame; and E is the grinder arbor which is mounted upon bearings F on said slide. The axis of the arbor E is transverse to the axis of the arbor B, and provision is made for adjustment of both the plane of the grinder and of the work.

For adjusting the work-holding arbor B, it is provided with a telescopic extension B', which has threaded engagement with the main section and is held in different positions of adjustment by a lock-nut B². This section B' has a shank portion B³ on which the work is placed, a clamping-nut B⁴ engaging a threaded portion of said shank B³ serving to clamp the work, and a bushing-collar B⁵ centering the same.

Upon the lower end of the arbor B is mounted an indexing disk G, which is provided with a plurality of series of accurately-spaced apertures a at different radial distances from the center.

G' is a reciprocatory rocker member, fulcrumed upon the arbor B, and carrying a dog G³ for engaging the apertures a in the index plate. This dog is mounted in an adjustable block G⁴, slidably engaging the rocker-arm G', and provided with a shank G⁵ for adjusting it inward or outward. The shank is provided with a series of notches G⁶ which are engaged by a pointed pin G⁷ engaging a bearing G⁸ on the rocker G', and held in engagement by a threaded plug G⁹ bearing thereagainst; while a spring G¹⁰ serves to disengage said pin when the pressure is released. Thus, by engaging the pin in different notches G⁶, the dog G³ is registered with different series of apertures.

For reciprocating the rocker G' and for engaging and disengaging the dog G³ cams are provided which are preferably arranged upon a common shaft H. This shaft extends transversely of the frame A and is driven by any suitable mechanism (not shown).

H' is a cam upon the shaft H, which engages a reciprocatory slide I mounted in the frame, said slide having a transversely-extending slot I' therein.

I² is a pin having a squared portion *b* engaging the slot **I'** and a rounded portion *c* passing through the adjustable block **G⁴** and hollow to receive the dog **G³**.

I³ is a spring operating upon the slide **I** in a direction opposed to the cam **H'**, the arrangement being such that during the rotation of the cam the slide **I** will be reciprocated, which will impart a reciprocating movement to the pin **I²**, block **G⁴**, rocker **G'** and dog **G³**; while the segmental path of movement of the rocker, pin and dog is permitted by a transverse sliding movement of the pin in the slot **I'**. Upon the slide **I** is mounted a rock shaft **J**, having a rock-arm **J'** feathered thereon, said rock-arm being attached at its outer end to the shank of the dog **G³**.

J² is a second rock-arm attached to the shaft **J**, and which extends into operative relation to a cam **H²** upon the cam shaft **H**. The cam **H²** is so timed as to actuate the rock-arm **J²**, and through the medium of the rock-arm **J'** will withdraw the dog **G³** after the completion of the forward movement of the slide **I** and before the return thereof. Thus through the combined action of the cams **H'** and **H²** the index disk **G** is periodically rotated with a step-by-step movement, which adjusts the work upon the holder **B** to different positions for grinding.

For moving the grinder into engagement with the work and for withdrawing the same when the work holder is to be adjusted, an intermittent, reciprocatory movement is imparted to the slide **C**. As shown, the shaft **H** has mounted thereon an eccentric **H³** engaging a rod **K**, which is connected to a threaded rod **L**. This threaded rod is engaged by a correspondingly threaded socket member **L'**, which is rotatively secured in a bearing **M** upon a slide **M'**. The slide **M'** is adjustably connected to the slide **C**, through the medium of a clamping bolt **N**, which has a head **N'** engaging an under-cut slot **N²** in the slide **M'**, so that by tightening the bolt the two slides will be clamped together. When, however, the bolt **N** is loosened the slide **C** may be adjusted independently of the slide **M'**, which permits of setting the grinder in relation to the work.

The screw-threaded rod **L**, in conjunction with the threaded socket member **L'**, forms a feed mechanism for gradually changing the limit of inward movement of the grinder, so that the grinding cuts will be successively deepened. This feeding is effected by the rotation of the socket member **L'** in its bearing **M**, which in turn is operated by mechanism of the following construction: **L²** is an extension of the member **L'**, which is socketed to telescopically engage a rod **O**, which is rotatively fixed by a feather **O'**. The rod **O** extends through a bearing **O²** in the frame and is connected by a worm-gearing **P** with a shaft **P'**, having a ratchet-wheel **P²** thereon. **Q** is a ratchet-lever carrying a dog **Q'** for engaging the ratchet-wheel **P²**, said lever being fulcrumed upon the shaft **P'** and being intermittently reciprocated by a rod **Q³** connected to a lever **Q⁴**, extending into the path of a cam **Q⁵** on the periphery of the indexing disk **G**. Thus once in each complete revolution of said indexing disk the cam **Q⁵** will actuate the lever **Q⁴**, rod **Q³**, ratchet-lever **Q** and dog **Q'**, to impart a rotative movement to the ratchet-wheel **P²** and shaft **P'**. The amount of feed may be varied by changing the point of attachment of the rod **Q³** to the ratchet-lever **Q**, and, as shown, a plurality of apertures **Q²** are formed in the lever for engagement of the connecting pin.

With the mechanism just described, the depth of cut of the grinder is increased after each complete revolution of the work-holder, and this continues until the required depth is obtained. To prevent over-cutting I have provided means for automatically throwing out the feed mechanism, which may be set for any required depth of cut. This comprises a rotating cam or trip-lever **R**, mounted upon the ratchet-lever **Q**, and connected to a notched feed-wheel **R'** engaged by a wheel **R²** on the shaft **P'**.

R³ is a tooth on the wheel **R²**, which once in each revolution of the latter engages a notch in the wheel **R'**, imparting a limited rotative movement thereto before disengagement. The trip-lever **R** is adapted to engage with a pin or lug **S** upon the dog **Q'** to withdraw said dog from the ratchet-wheel **P**. Said member **R** is also preferably clamped to the wheel **R'** so as to permit of a relative adjustment thereon, and the arrangement is such that by properly setting the member **R** any desired degree of feed may be imparted to the grinder before the dog **Q'** will be disengaged and further feed prevented.

With the construction as described in use, the operation is as follows: The worm milling-cutter or other blank to be re-cut, is first placed upon the work-holding spindle **B** and the latter is longitudinally adjusted if necessary to properly center the blank in relation to the arbor of the grinder, this adjustment being effected by screwing the member **B'** upon the member **B** and clamping by the lock-nut **B²**. When the work is properly set, the grinder wheel is set in relation thereto by loosening the clamping bolt **N**, and adjusting the grinder wheel into contact with the periphery of the blank; while the slide **M'** is at the limit of its inward movement. The clamping bolt **N** is then tightened, after which the machine may be set into operation. During the operation the rotation of the cam shaft **H** will cause the

reciprocation of the slides M' and C through the medium of the eccentric H³ and rods K and L; and during the interval when the slides are at the outer end of their movement the cams H' and H² will operate to effect an adjustment of the index mechanism. Thus each time the slide C is moved inward to carry the grinder wheel in to the work, it will effect a grinding of a different portion of the periphery of the blank until the completion of a revolution of the latter. When this occurs the cam Q⁵, operating the lever Q⁴, rod Q³ and ratchet-lever Q, will cause a rotation of the ratchet-wheel P², shaft P', worm-gearing P and rod O, the latter communicating movement from the feather O' and extension L² to the member L', which is slightly rotatively adjusted. Thus a feed, preferably varying from one to five or six thousandths, is produced, which will correspondingly deepen the grinding cuts in the second revolution of the blank; and the operation will thus continue until the trip-lever D disengages the dog Q' from the ratchet-wheel P², which will stop further action. The blank may then be disengaged from the spindle B and the machine re-set by turning back the feed mechanism through the medium of a knob or handle P⁴ on the shaft P'.

It is desirable to provide means of adjusting the grinder wheel axially to suit the requirements of different blanks, and to this end we have provided the following construction: The grinder arbor E is journaled in the bearings F, and comprises an inner shaft E' and a surrounding sleeve E². The clamping collars E³ for the grinder wheel are secured to the member E', while the journals and the drive-pulley E⁴ are upon the sleeve member E². E⁵ is a shank extending outward from the shaft E' beyond one of the bearings F, and carrying at its outer end an anti-friction, ball thrust bearing T, which is carried by a housing T'. This housing T' is attached to a threaded sleeve T² surrounding the shank E⁵ and engaging a nut T³ arranged between furcations of one of the bearings F. The arrangement is such that by adjusting the nut T³, the sleeve T² will be moved longitudinally and will carry with it the shank E⁵ and shaft E', thereby adjusting the position of the grinder wheel.

What we claim as our invention is:

1. A grinding machine comprising a rotative work-holder, a rotary grinder arranged in a transverse plane, means for intermittently, relatively reciprocating said work-holder and grinder to move the latter toward and from the periphery of the work, and means operating when the grinder is withdrawn from engagement with the work for adjusting said work-holder rotatively, to present a different portion of the periphery of the work to said grinder, and

feed mechanism for periodically increasing the depth of the cut.

2. A grinding machine comprising a rotative work-holder, a rotary grinder arranged in a transverse plane, means for relatively reciprocating said work-holder and grinder to move the latter toward and from the periphery of the work, means operating during the interval when said grinder is withdrawn from the work, for rotatively adjusting said work-holder, to present a different portion of the periphery of the work to said grinder, and means operating in each cycle of the work-holder for changing the limit of inward movement of said grinder to increase the depth of the cut.

3. A grinding machine comprising a rotative work-holder, a rotary grinder arranged in a transverse plane, means for relatively reciprocating said work-holder and grinder to move the latter toward and from the periphery of the work, means operating during the interval in which the grinder is withdrawn from the work for rotatively adjusting said work-holder, and feed mechanism arranged intermediate the grinder and its reciprocating means to periodically increase the depth of the cut.

4. A grinding machine comprising a rotative work-holder, a rotary grinder arranged in a transverse plane, means for reciprocating said grinder to move the same toward and from the periphery of the work, means operating during the interval in which the grinder is withdrawn from the work for rotatively adjusting said work-holder, feed mechanism arranged intermediate said grinder and its reciprocating means, and means operating once in each cycle of said rotary work-holder for operating said feeding means to adjust inward the limit of movement of said grinder.

5. A grinding machine comprising a rotative work-holder, a rotary grinder arranged in a transverse plane, a reciprocatory carriage on which said grinder is mounted, adapted to move the latter toward and from the periphery of the work, a reciprocating member, an adjustable connection between said reciprocating member and said reciprocatory carriage, permitting of the adjustment of the latter with relation to the work, feed mechanism operating once in each cycle of said rotative work-holder for changing the inward limit of movement of said reciprocating member, and means for limiting the operation of said feed mechanism.

6. A grinding machine comprising a frame, a reciprocatory slide mounted on said frame, a rotating arbor mounted on said slide, a grinder-wheel mounted on said arbor, a rotative work-holder having its axis transverse to the axis of said arbor, means for adjusting the work axially of said work-holder, means for adjusting the grinder ax-

ially of said arbor, means for reciprocating said slide to move said grinder toward and from the periphery of the work, indexing mechanism for the rotative adjustment of 5 said work-holder, and means for operating said indexing mechanism during the interval in which said grinder is withdrawn from said work.

7. A grinding machine comprising a rotative work-holder, a reciprocatory slide in a 10 plane transverse to the axis of said work-holder, an arbor mounted on said slide, a grinder wheel mounted on said arbor, a rotary shaft, a crank-and-pitman-rod connection 15 between said shaft and said reciprocatory slide for actuating the latter, an indexing disk upon said rotary work-holder, a reciprocatory pawl for adjusting said indexing disk, and a cam on said rotary shaft for 20 controlling the operation of said pawl during the interval in which said grinder wheel is withdrawn from the work.

8. A grinding machine comprising a 25 frame, a reciprocatory slide thereon, a grinding arbor and grinding wheel mounted upon said slide, a rotative work-holder having its axis transverse to the axis of said arbor, a reciprocating member connected with said slide, a screw feed mechanism intermediate 30 said reciprocating member and said slide, an indexing mechanism for said rotary work-holder, and a cam on said in-

dexing mechanism operating once during each cycle thereof for adjusting said screw feed mechanism.

9. A grinding machine comprising a frame, a reciprocatory slide mounted on said frame, a rotative work-holder arranged with its axis transverse to the plane of said slide, a grinding arbor and grinder wheel mounted 40 on said slide and movable therewith toward and from the periphery of the work on said work-holder, an indexing disk on said work-holder, a reciprocatory slide adjacent to said disk, a pawl carried by said slide and laterally movable thereon for engaging said indexing disk, a rotary shaft, a cam on said shaft for intermittently reciprocating said pawl-carrying slide, a co-operating cam on said shaft for disengaging said pawl from 45 said disk, a crank-and-rod connection between said shaft and said arbor-carrying slide for reciprocating the latter, a feed screw in said rod connection for changing the limit of reciprocatory movement, and a cam on said indexing disk for operating said feed screw once in each cycle of the disk.

In testimony whereof we affix our signatures in presence of two witnesses.

RAGNVALD M. NICOLAYSEN.
HARLEY H. LA VERCOMBE.
